WELL PUMP

Edward T. Adams, Los Angeles, Calif., assignor
to Edward E. Adams, Los Angeles, Calif.

Application September 27, 1938, Serial No. 231,878

10 Claims. (Cl. 103—204)

This invention relates to pumps and relates more particularly to pumps for use in deep wells such as oil wells. A general object of this invention is to provide a simple, practical and efficient 5 pump that is inexpensive to construct and maintain in operation.

This application is a continuation in part of my copending application for Letters Patent, Serial No. 168,428, filed October 11, 1937, entitled "Well 10 pump," patented June 6, 1939, No. 2,160,811.

My copending application, referred to above, describes and claims a well pump embodying a relatively reciprocable barrel and plunger assembly, having two vertically spaced zones of sealing 15 cooperation, the upper sealing zone being larger in diameter than the lower sealing zone and the plunger and barrel defining an annular silt trapping space between the zones of sealing cooperation, which space is vented to the interior of the 20 plunger at points spaced between spaced traveling valves in the plunger. A construction of this nature provides for the grinding of the silt and other solid matter by the elements of the upper sealing zone and provides for the washing of 25 the solid matter from the annular space to prevent such solid matter from reaching the lower sealing zone. The volume of the annular space in a pump of the character referred to depends upon the difference in diameters of the tubular 30 stock of which the barrel and plunger are constructed and the lengths of the barrel and plunger, and under certain operating conditions this annular space may be of substantial volume. However, in other cases where it is desirable to 35 employ a shorter pump or a cheaper pump the employment of a barrel and plunger assembly of two diameters to provide the annular silt trapping space may be prohibited. The present invention provides a well pump embodying a barrel 40 and plunger of uniform diameters having upper and lower sealing zones and having an annular space for trapping the solid matter that may pass the upper sealing zone to prevent such matter from reaching the lower principal sealing zone 45 and embodies means for assuring the flushing of the solid matter from said space. The pump of the present invention embodying the barrel and plunger of uniform diameters, is cheaper to manufacture and may be shorter than a pump having 50 a barrel and plunger of two diameters.

Another object of this invention is to provide a highly efficient and long wearing well pump.

Another object of this invention is to provide a well pump of the character referred to embodying 55 simple, practical and dependable means for pre-

venting solid matter from reaching the principal or lower zone of sealing engagement between the barrel and plunger to prevent the wearing of the active sealing surfaces.

Another object of this invention is to provide a 5 well pump of the character mentioned embodying means for scraping, scouring and washing the wall of the barrel to remove silt or other solid matter that may adhere thereto to prevent such material from reaching the lower or principal 10 sealing zone of the pump.

Another object of this invention is to provide a well pump of the character mentioned in which the solid matter is scraped from the wall of the 15 pump barrel during both the down stroke and the up stroke and the annular space receiving this solid matter is flushed or washed free of the same during each complete cycle of operation.

Another object of this invention is to provide a 20 pump of the character mentioned in which the flow of fluid through the silt trapping annular space is assured by a positive fluid flow or by an induced flow.

Another object of this invention is to provide a 25 pump of the character mentioned embodying novel means for producing a positive flow of fluid through the annular silt-trapping space.

Another object of this invention is to provide a 30 pump of the character mentioned having means for creating a turbulent rotary flow of fluid through the annular silt-trapping space to assure the removal of all solid matter from the space.

The various objects and features of my invention 35 will be fully understood from the following detailed description of typical preferred forms and applications of the invention, throughout which description reference is made to the accompanying drawing, in which:

Fig. 1 is a central longitudinal detailed sectional view of the major portion of one form of pump of the invention. Fig. 2 is a central sectional longitudinal diagrammatic view of the pump illustrated in Fig. 1. Fig. 3 is an enlarged horizontal detailed sectional view taken as indicated by line 3—3 on Fig. 1. Fig. 4 is an enlarged fragmentary vertical detailed sectional view of a portion of another form of pump of the invention, and Fig. 5 is a transverse detailed sectional view taken substantially as indicated by line 5—5 50 on Fig. 4.

The form of pump of the present invention illustrated in Figs. 1, 2 and 3 of the drawing may be said to comprise, generally, a barrel 10 having a foot valve 11, a reciprocable plunger 12 operable 55

in the barrel 10 and carrying two working valves or traveling valves 13 and 14, the barrel and plunger cooperating to provide two spaced sealing zones A and B and an annular fluid chamber 5 C between the zones A and B, and means D for producing or inducing a flow of fluid through the space C.

In accordance with the invention the barrel 10 of the pump may be an elongate tubular member of uniform internal diameter. In the form of the invention illustrated the barrel 10 is the stationary element of the pump and the plunger 12 reciprocates in the barrel. It is to be understood that the present invention may be embodied in the standing plunger and working barrel type of pump, if desired. As diagrammatically illustrated in Fig. 2 of the drawing, the barrel 10 may be suspended from its upper end by a top lock. The top lock for the barrel 10 10 comprises a mandrel part 18 cooperating with a shoe 19 on the lower end of the well tubing T. The lower end of the mandrel part 18 forms a downwardly facing lifting shoulder 20 at the upper end of the pump barrel 10. The standing 15 valve or foot valve 11 is preferably provided on the lower end of the barrel 10. The foot valve 11 may be of any selected or preferred type. In the construction illustrated the valve 11 is a simple ball valve comprising a tubular cage 21 20 threadedly connected with the lower end of the barrel 10 and a ball 23 in the cage 21 adapted to engage downwardly against an internal seat 22.

The plunger 12 is the moving or reciprocating element of the well pump and operates longitudinally in the barrel 10. The plunger 12 is preferably sectional comprising two or more tubular sections. In the form of the invention illustrated in the drawing the plunger 12 includes an upper section 24 and a lower section 25 connected by an adapter section or connecting section 26. The sections 24 and 25 are of the same effective external diameter and may, if desired, be of uniform diameter throughout their lengths. The plunger sections 24 and 25 have sealing cooperation with the internal surface of the barrel 10 at the sealing zones A and B, that is, the section 24 cooperates with the barrel 10 to provide the sealing zone A and the section 25 cooperates with the barrel 10 to provide the sealing zone B. The upper plunger section 24 may be varied considerably in length for the reasons to be herein-after set forth, and may be provided with sealing means for cooperating with the internal surface of the barrel 10. In the construction illustrated the upper plunger section 24 is provided with vertically spaced annular liquid carrying grooves 28 in the sealing portion of the upper plunger section 24. If desired or believed necessary the lower plunger section 25 may be provided with any suitable form of sealing means for cooperating with the barrel 10 at the sealing zone B. In the case illustrated, however, the lower plunger section 25 has a plain finished cylindrical external surface operating in the barrel 10 with but slight tolerance. The tolerance between the sealing surfaces of the plunger section 25 and the barrel 10 depends upon several factors such as the length of the plunger section, the character of the fluid handled, etc.

70 The coupling or connecting section 26 serves to connect the two sealing sections 24 and 25 of the plunger 12. The connecting section 26 connects the opposing ends of the sections 24 and 25 in such a manner that the sections 24 and 25 are 75 spaced apart to provide or leave the annular

silt-trapping space C. In accordance with the broader aspects of the invention the connecting section 26 may be connected with the sections 24 and 25 in any suitable manner. In the construction illustrated the upper portion of the connecting section 26 is threaded in the lower end portion of the section 24 and is threaded in the upper end portion of the section 25. As above described the section 26 holds the upper and lower sections 24 and 25 spaced apart to leave or provide the chamber C and the length or vertical dimension of the chamber C depends upon the length of the section 26. The connecting section 26 is considerably smaller in diameter than the sections 24 and 25 and the horizontal dimension of the chamber C depends upon the difference in diameters between the section 26 and the sections 24 and 25. It is to be observed that the silt-trapping chamber C occurs between the two sealing zones A and B.

The lower end of the upper plunger section 24 defines the upper wall of the chamber C and the upper end of the section 25 constitutes the lower wall of the chamber C. During the down stroke of the plunger 12 the lower end of the section 24 25 acts as a scraping surface 29 which scrapes silt and other solid matter from the wall of the barrel 10. In a like manner the upper end of the section 25 forms a scraping surface 30 which scrapes adhering silt, etc. from the surface of 30 the barrel 10 during the up stroke of the plunger 12. The material scraped from the barrel 10 by the surfaces 29 and 30 is received or deposited in the chamber C. The silt and other solid matter caught or trapped in the chamber C is washed 35 or flushed from the chamber into the main fluid handling passage of the pump by the means D, as will be subsequently described.

The traveling valves 13 and 14 are provided to control the flow of fluid through the plunger 12 and in the preferred construction are carried by the plunger to be spaced below and above the chamber C. The lower traveling valve 13 may comprise a tubular cage 35 threadedly connected with the lower end of the plunger section 25 and a replaceable valve seat 36 within the cage. A ball 37 is provided in the valve cage 35 and is adapted to seal downwardly against the seat 36. The valve 14 is arranged at the upper end of the plunger 12 and in practice may be secured to the upper end of the section 24. The upper traveling valve 14 may include a cage 38 containing a ball 39 for sealing downwardly against a seat 40. The cage 38 is ported or open to the interior of the barrel 10 and the tubing T above the seat 40. In practice the valve cage 38 may serve to connect the pump rod R with the plunger 12.

The means D operates to produce a particularly effective flushing or washing of the chamber C to remove all silt, sand, etc. therefrom. The means D provides or includes a Venturi tube opening 50 in the connecting section 26 of the plunger 12. The connecting section 26 is shaped and proportioned so that the passage or opening 50 extending therethrough is reduced in diameter, relative to the main fluid passage of the plunger 12, to have a Venturi tube action when the plunger 12 drops through the fluid in the barrel 10. The wall of the section 26 is thickened so that the opening 50 has an intermediate portion of reduced substantially uniform diameter and an upper portion 52 whose wall tapers upwardly and outwardly. The lower portion of the opening 50 may be of the same diameter as the passage 51 in the plunger section 25 and this low- 75

er portion of the opening 50 joins the restricted intermediate portion of the opening 50 at a downwardly facing shoulder 55. The shoulder 55 may be rounded off, as illustrated.

5 The means D further includes vertically spaced series of spaced ports 53 and 54 in the section 26 placing the chamber C in communication with the opening 50 and the main passage of the pump. The ports 53 communicate with the opening 50 10 at the shoulder 55 and their outer ends communicate with the lower end portion of the chamber C. As illustrated the ports 53 may slope downwardly and inwardly from the lower part of the chamber C to the shoulder 55 to have their upper ends 15 facing upwardly and outwardly and to have their lower ends facing downwardly and inwardly at the shoulder 55. The ports 54 extend through the wall of the section 26 from the tapered portion 52 of the opening 50 to the chamber C. In 20 the preferred construction the ports 54 have their inner ends adjacent the lower end of the tapered portion 52 of the opening 50 and have their outer ends at the upper portion of the chamber C.

In the operation of the pump illustrated in 25 Figs. 1, 2 and 3 of the drawing the pump rod R is reciprocated in the usual manner by a pump power or pump jack to operate the plunger 12 in the barrel 10. During the down stroke of the plunger 12 the standing valve 11 is closed and the 30 plunger drops down through the fluid in the barrel 10, the traveling valves 13 and 14 being open during the down travel of the plunger. The scraping surface 29 operates to scrape adhering solid matter from the wall of the barrel 10 as the plunger 12 moves downwardly and this solid matter is deposited or caught in the chamber C. The 35 relative movement of parts during the down travel of the plunger 12 is such that the reduced diameter Venturi passage or opening 50 produces an increase in the velocity of the fluid flowing through it and a decrease in the pressure at its tapered portion 52. This Venturi tube action induces a fluid flow through the ports 53 into the chamber C, through the chamber C and then out 40 through the ports 54. The fluid flow thus induced through the chamber C fully flushes all solid matter from the chamber as it is gathered by the scraping action of the surface 29. The fluid flowing upwardly through the chamber C washes 45 against the internal wall of the barrel 10 to wash free any solid matter that may remain adhering to the barrel. The upper section 24 of the plunger 12 acts as a grinder section to grind or reduce any solid matter that may be at the sealing zone 50 A. The ground or reduced solid matter thus formed is trapped or caught in the chamber C and carried away through the flow of fluid 55 through the chamber.

During the up stroke of the plunger 12 the 60 valves 13 and 14 are closed so that the plunger serves to raise the column of fluid in the tube T. The valve 11 opens during the up stroke of the plunger to admit fluid to the barrel 10 below the upwardly traveling plunger. The scraping edge 65 30 operates to scrape or clear the solid matter from the wall of the barrel 10 and this silt or solid matter is readily flushed from the chamber C by the fluid flowing through the chamber during the next down stroke of the plunger. Owing 70 to the presence of the valve 14 there is a tendency for fluid to slip through or past the sealing zone A and this fluid slippage may wash or carry solid matter through the sealing zone A to the chamber C. The chamber C operates to trap such solid 75 matter and prevents the solid matter from reach-

ing the lower sealing zone B. It will be seen that the chamber C, the scraping surfaces 29 and 30 and the means D circulating fluid through the chamber C prevent solid matter from reaching the sealing zone B and protect the section 25 of the plunger 12 against wear. The chamber C is ported to the main passage of the pump so that the silt and solid matter that may tend to accumulate therein by reason of the action of the surfaces 29 and 30 is flushed away during each 10 pumping cycle and does not remain in the chamber. The lower sealing zone B being protected against the action of the abrasive solid matter remains effective for a long period and has less 15 tendency to wear.

The upper sealing zone A acts as a protector for the lower sealing zone B, that is, the plunger section 24 operates as a grinder section to grind or reduce the particles of solid matter that are carried past it with the slippage of fluid. This 20 grinding action of the section 24 prevents large particles of solid matter from reaching the sealing zone B. Where the pump is employed to handle a fluid containing a large percentage of solid matter the lower protective sealing zone B 25 may be increased in length, that is, the plunger section 25 may be increased in length to provide a longer seal. In this case the upper section 24 of the plunger 12 may serve primarily as a grinder and scraper section and may be 30 shortened and the lower section 25 may be lengthened. Where the upper plunger section 24 is materially shortened and the lower plunger section 25 is lengthened to adapt the pump for the handling of fluid containing a large percentage of solid matter, the upper traveling valve 14 may, if desired, be dispensed with for in this case the sealing action of the upper section is so reduced that the extra expense of the upper valve 14 may not be justified. In any application 40 of the pump the upper section 24 of the plunger 12 operates as a grinder section to reduce the particles of solid matter adhering to the barrel walls and entrained with the slippage fluid and the surfaces 29 and 30 operate as scrapers or 45 wipers to remove adhering solid matter from the walls of the barrel 10. The chamber C always operates as a trap for the solid matter that may slip past the grinder section 24 and that is scraped off by the surfaces 29 and 30. As above 50 described, the ports 53 and 54 and the Venturi tube opening 50-52 assure the removal or flushing away of all of the solid matter from the chamber C and the transference of such solid matter to the main fluid handling passage of 55 the pump.

Figs. 4 and 5 of the drawing illustrate a form of the invention in which a positive flow of fluid is provided to flush or carry the solid matter from the silt trapping chamber. In the construction illustrated in Figs. 4 and 5 of the drawing the barrel 10 with its foot valve 11 and the plunger 12 with its traveling valves 13 and 14 may be the same as described above. The coupling section or connecting section 26^a of this 60 arrangement connects the two plunger sections 24 and 25 in the same manner as the above described connecting section 26. The connecting section 26^a is smaller in external diameter than the plunger sections 24 and 25 and holds the opposing ends of the sections 24 and 25 in spaced relation to provide the silt trapping chamber C'. It is preferred to slope or pitch the end or scraping surface 29^a of the plunger section 24 to have 65 effective scraping engagement with the internal 70 75

surface of the barrel 10. The surface 28^a is preferably sloped downwardly and outwardly. The scraping surface 38^a of the plunger section 25 is preferably sloped downwardly and inwardly to have an efficient scraping action. The connecting section 28^a of the plunger 12 is in the form of a block or plug having a transverse internal partition 60 separating the passage 51 of the plunger section 25 from the passage 61 of the upper plunger section 24.

The construction illustrated in Figs. 4 and 5 of the drawing embodies a novel means D' for producing a positive flow of fluid through the silt trapping chamber C'. The means D' includes a set or series of ports 62 in the section 28^a venting the chamber C' to the passage 61 in the upper section 24 of the plunger 12. The ports 62 extend laterally through the section 28^a and are circumferentially spaced one from the other. In the preferred construction the ports 62 have their outer ends in communication with the upper part of the chamber C' and have their inner ends in communication with a socket 63 which in turn joins the bottom of the passage 61. The ports 62 are preferably pitched downwardly and outwardly as illustrated.

The means D' further includes a set or series of ports 64 in the connecting section 28^a connecting the chamber C' with the passage 51 in the lower plunger section 25. The ports 64 are circumferentially spaced and preferably slope downwardly and inwardly from the lower part of the chamber C' to a socket 65 in the lower end of the section 28^a. The socket 65 has full communication with the passage 51 so that the ports 64 are in communication with said passage. In accordance with the invention the ports 64 are such that the fluid is given a rotary or spiralled motion as it enters the chamber C'. The ports 64 in addition to being pitched downwardly and inwardly are pitched tangentially with respect to a circle concentric with the central vertical axis of the pump. The several ports 64 are preferably tangentially pitched in the same direction and at the same angle. It will be seen that fluid flowing upwardly and outwardly through the tangentially pitched ports 64 is given a swirling motion to spiral upwardly through the chamber C'.

In the operation of the construction illustrated in Figs. 4 and 5 of the drawing the barrel 10, valve 11, plunger 12 and valves 13 and 14 operate in the same manner as in the previously described embodiment of the invention. During the down stroke of the plunger 12 in the barrel 10 the relative movement of the parts produces an upward flow of fluid through the plunger 12. The fluid from the passage 51 flows through the ports 64 into the chamber C'. The fluid passed through the ports 64 is directed upwardly and outwardly and is given a rotary or whirling motion. This rotary motion of the fluid in the chamber C' is created on the down stroke of the plunger 12 and persists through the up stroke to form a turbulent flow holding the solid matter in suspension in the liquid. This whirling fluid directed upwardly and outwardly has an effective scouring and washing engagement with the wall of the barrel 10 to thoroughly wash all adhering solid matter from the barrel. The fluid rotating or spiralling in the chamber C' entrains or picks up the solid matter that may be in the chamber and carries it out through the ports 62 to the passage 61. The surface 28^a operates to scrape solid matter from the wall of the barrel 10 during

the down stroke of the plunger 12 and the solid matter scraped or wiped off by the surface 28^a is carried away by the fluid flowing through the chamber C'. It is to be observed that there is a positive flow of fluid through the chamber C' to completely carry off all the solid matter from the chamber. During the up stroke of the plunger 12 the scraping surface 38^a operates to remove adhering solid matter from the wall of the barrel 10 and this solid matter may be deposited in the chamber C'. The grinder section 24 of the plunger 12 operates to reduce or grind the solid matter at the sealing zone A and this reduced solid matter and any other solid matter that may be carried with the slippage fluid is caught or trapped in the chamber C'. The positive flow of fluid through the chamber C' during the next down stroke of the plunger 12 completely flushes the chamber of all accumulated solid matter.

It is to be understood that in both of the above described forms of the invention the barrel 10 and the plunger 12, or at least the parts of the plunger 12 adjacent the groove C or C' are formed of metal to provide the metal to metal engagement and the metal scraping edges herein described.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. A well pump comprising, a barrel valved at its lower end, a tubular plunger reciprocable in the barrel and having an external groove between its ends forming a fluid chamber, the barrel and plunger having sealing cooperation at zones above and below said chamber, a restriction on the interior of the plunger providing the plunger with a Venturi passage, the plunger having ports communicating with the chamber and with the Venturi passage at vertically spaced points, and a valve on the plunger controlling flow through the plunger.

2. A well pump comprising, a barrel valved at its lower end, a tubular plunger reciprocable in the barrel and comprising two tube sections, and a member of reduced external diameter connecting the sections, there being an annular chamber between the adjacent ends of the sections, the sections having sealing engagement with the barrel at zones above and below the chamber, a Venturi restriction on the interior of the member, the member having vertically spaced ports communicating with the chamber and said Venturi restriction, and valves on the plunger above and below said ports.

3. A well pump comprising a barrel having a foot valve, a tubular plunger reciprocable in the barrel above the foot valve and having an external annular groove between its ends and longitudinally spaced ports connecting the groove with the interior of the plunger, the plunger including a grinder portion above the groove for grinding solid matter that may slip past the plunger into the groove and a sealing portion below the groove operating in sealing relation to the barrel, a valve on the plunger controlling flow therethrough, and means for producing a flow of fluid through the ports and groove during the down stroke of the plunger to remove solid matter from the groove.

4. A well pump comprising a barrel having a foot valve, a tubular plunger reciprocable in the

barrel above the foot valve and having an external groove between its ends, the plunger including a grinder portion above the groove for grinding solid matter that may slip past the plunger into the groove, a portion below the groove in sealing relation to the barrel, and a partition across the interior of the tubular plunger, the plunger having ports communicating with the groove and communicating with the interior of the plunger above and below said partition to circulate fluid through the groove, and a valve in the plunger below the groove to control the flow through the plunger.

5. A well pump comprising a barrel having a foot valve, a tubular plunger reciprocable in the barrel above the foot valve and having an external annular groove between its ends, the plunger including a scraping element above the groove for scraping material from the barrel wall into the groove, a sealing portion below the groove in sealing relation to the barrel, and a partition across the interior of the tubular plunger, the plunger having a port communicating with the groove and communicating with the interior of the plunger above the partition and a port communicating with the groove and communicating with the interior of the plunger below said partition, the last named port being directed to give the fluid entering the groove a whirling motion.

6. A well pump comprising a barrel having a foot valve, a tubular plunger reciprocable in the barrel above the foot valve and having an external groove between its ends, a scraper part on the plunger for scraping material from the wall of the barrel into the groove, a partition across the interior of the plunger, the plunger having a series of ports extending from the upper part of the groove to the interior of the plunger above the partition and a series of ports extending from the lower part of the groove to the interior of the plunger below the partition, said ports circulating fluid through the groove to remove said material therefrom, and valves on the plunger above and below said partition controlling fluid flow through the plunger.

7. A well pump comprising a barrel valved at its lower end, a tubular plunger reciprocable in the barrel and having an external groove forming a fluid chamber and longitudinally spaced ports maintaining its interior in communication with the chamber, the barrel and plunger being of uniform effective diameter and having sealing cooperation below the chamber, a grinder portion on the plunger above the chamber cooperable with the barrel to grind up solid matter particles that may enter between the barrel and plunger surfaces, means producing a flow of fluid from the interior of the plunger through the ports

and chamber and back into the plunger during operation of the plunger, and a traveling valve on the plunger.

8. A well pump comprising a barrel valved at its lower end, a tubular plunger reciprocable in the barrel and comprising upper and lower tube sections, and a member of reduced external diameter connecting the sections, the differential in diameter of the sections and member providing an external chamber between the opposing ends of the sections, the upper section operating in the barrel as a grinder to reduce solid particles, the lower section having sealing engagement in the barrel below the chamber, the member having ports connecting the upper and lower portions of the chamber with the interior of the plunger, means in the member producing a positive flow of fluid from the interior of the plunger through the ports and chamber and back into the plunger during the down stroke of the plunger, and valves in the plunger above and below the ports controlling flow through the plunger.

9. A well pump comprising a tubular barrel having a foot valve, a tubular plunger reciprocable in the barrel above the foot valve, the tubular barrel and plunger defining a passage for a column of the fluid being pumped, the plunger having an external groove, a partition in the plunger, a metal scraping edge on the plunger for scraping material from the wall of the barrel into the groove, port means in the plunger placing the groove in communication with the said passage above and below the partition whereby the fluid of said column flows through the port means and groove to flush out the same during the down stroke of the plunger, and a traveling valve on the plunger controlling the flow therethrough.

10. A well pump comprising a barrel having a foot valve, a tubular plunger reciprocable in the barrel above the foot valve and having a circumferential fluid channel between its ends, scraper parts on the plunger below and above the channel having metal to metal engagement with the barrel for scraping material from the wall of the barrel into the channel, a partition across the interior of the plunger, the plunger having a port extending from the upper part of the channel to the interior of the plunger above the partition and a port extending from the lower part of the channel to the interior of the plunger below the partition, said ports circulating fluid through the channel to remove said material therefrom, the last named ports being directed to give the fluid a swirling motion in the channel, and a valve on the plunger controlling flow therethrough.

EDWARD T. ADAMS.
